M. SCHIESARI

APPARATUS FOR THE REMOVAL OF SNOW

Filed March 6, 1923

UNITED STATES PATENT OFFICE.

MARIO SCHIESARI, OF NEW YORK, N. Y.,

APPARATUS FOR THE REMOVAL OF SNOW.

Application filed March 6, 1923. Serial No. 623,213.

To all whom it may concern:

Be it known that I, MARIO SCHIESARI, a citizen of the United States, residing in the city of New York, county and State 5 of New York, have invented certain new and useful Improvements in Apparatus for the Removal of Snow, of which the following is a full, clear, and exact description, reference being had to the accompanying 10 drawings, forming a part of this specification.

This invention relates to apparatus for the removal of snow from streets and other thoroughfares where water and sewers are 15 available, and more particularly refers to improvements over apparatus for the same purpose described and claimed by me in a co-pending application entitled "Method of and apparatus for removing snow," filed by 20 me on October 28, 1922, Serial No. 603,880.

The main object of this invention is to provide a novel and improved arrangement of the snow receiving chamber in devices such as described in the above-entitled application, whereby the disposal of the snow 25 collected may be effected in a more rapid and efficient manner.

A further object is to provide a novel arrangement of discharging means for said 30 chamber, whereby a quick discharge of the snow will be facilitated, and the possibility of clogging of the outlets considerably lessened.

Other objects will more fully appear as 35 the description proceeds, and will be pointed out and claimed in the appended claims.

In the co-pending application above referred to, I described various types of devices whereby the snow may be collected 40 and directed or fed in the path of a stream of water under pressure, for which an exhaust conduit, conveniently placed in relation to the line of travel of said water, is provided.

In some of the devices shown, mechanical 45 means for effecting a fractional and gradual feeding of the snow in the path of a stream of water issuing from a nozzle, have been illustrated, while in others no such 50 means have been provided, the snow being fed to the water in bulk.

The chamber proper, where the snow is 55 actually directed for ultimate disposal, is however constituted by a single receptacle within which the stream issuing from the

nozzle is also directed. Said chamber has been illustrated provided with one outlet, to which a discharge tube leading to the sewer may be attached; and I have found in practice with such an arrangement, that 60 clogging at the discharge outlet may easily take place, even in such devices where the snow is fed in fractional quantities by mechanical contrivances, if the same are run at the high speed which would be desirable. 65

The main object of the present invention is to eliminate as far as possible such a condition, and to insure a speedy and efficient operation of the device, by a cellular construction of the snow chamber, a corresponding subdivision of the stream of water in a number of elementary streams fed by individual nozzles into said cells, and individual outlets for each cell, leading to a main collector; or, in other words, by subdividing the mass of snow which is fed to the chamber, by exerting the action of the water on the same simultaneously at a number of points, and by accordingly multiplying the points of outlet. 70 75 80

In this manner, a mass of snow is attacked by the water simultaneously at various points, and is more rapidly dissolved and carried away; said action of the water being further facilitated by the fractioning 85 of the snow which has previously taken place, and by the possibility of the discharge being effected simultaneously at various points.

In the drawings, which are intended for 90 illustrative purposes only, and not in a limiting sense, I show a typical arrangement of device embodying my invention; and in the same,

Fig. 1 is a front view in elevation, partly 95 sectioned and broken away, of a device of the hand operated type;

Fig. 2 is a side view in elevation of the same, partly sectioned and broken away;

Fig. 3 is a detail view in perspective of a 100 blade-like valve for the snow chamber; and,

Fig. 4 is a view in perspective of a street in which two of the devices illustrated are shown in simultaneous operation.

The device illustrated, consists of a funnel shaped shovel or scoop 10 provided with a handle 11, by means of which the same may be propelled on the pavement, collecting snow as it proceeds. The rear part 12 105 of the scoop, which constitutes the snow 110

chamber proper, is subdivided in a plurality of elementary chambers or cells 13, by partitions 14 running from front to rear.

15 designates a crosswise running water distributor which may be connected to a street hydrant by means of flexible conduit 16, and which is provided with a plurality of nozzles 17, one for each chamber 13. Said nozzles direct a stream of water towards the rear of each elementary chamber or cell 13, each stream, therefore exerting its action on the snow contained in such elementary cells.

15 Each cell is furthermore provided with an individual outlet 18, at the rear, and directly opposite to nozzles 17, through which the combined water and snow are carried by the force of the water; said outlet leading to a common collector 19 to which may be attached a flexible conduit 20 directing the water and snow to the sewer.

Said collector 19 is provided with a shoe 20, supporting the weight of the same, and enabling the device to slide easily on the ground.

30 The quantity of snow against which each elementary stream is directed being small, the discharge of the same will easily take place without clogging of outlets, and without water overflowing from the front of the scoop. The snow chamber however, may preferably be physically divided from the front part of the scoop by a blade valve 21, pivoted at 22, and provided with notches 35 23 corresponding to partitions 14, so that whenever a partial clogging should nevertheless take place, the snow chamber may be closed, and water prevented from overflowing.

40 To this end, shaft 24, on which blade valve 21 is mounted, is provided at each end with a cam shoe 25, which maintains blade valve 21 open when the device is propelled forward, and will close it if the device is moved backward; in such case the blade valve assuming the position shown in Fig. 2.

45 In such a position, the full pressure of the water will be exerted against the snow obstructing the passage and this will ordinarily be sufficient to gradually force it through the outlet, clearing the same.

50 In Fig. 4 it is shown how a plurality of devices may be connected for simultaneous operation to a common supply tube 26 attached to a hydrant 27, and to a common discharge tube 28, leading to a sewer opening 29.

The handle 11 has an inverted U shape, so that the device may be operated by either 60 one or two men, according to the depth and consistency of the snow.

65 A similar sectional arrangement of the snow chamber may of course be adopted, together with the multiple nozzle feed and multiple discharge, in connection with de-

vices of design other than the one shown, and in connection with devices operated by power or by animal traction. Various types of such devices have been illustrated and described in the co-pending application 70 above referred to, and no more than reference to the same is therefore considered necessary.

It may be noted that some of the devices referred to are provided with mechanical 75 feeding means directing or discharging the snow in a snow chamber which is closed instead of open as in the device described herein; and it is obvious that the same principle of cellular construction and multiple 80 distribution and discharge can equally well be applied in such devices.

The novel and useful features of my invention are made apparent by the above 85 description, and may of course be embodied in devices of various types and descriptions without departing from the spirit of the same, and remaining within the scope of the appended claims.

I claim:

1. In a device of the class described, the combination with water feeding means, of a plurality of cellular compartments in the path of the water issuing therefrom.
2. In a device of the class described, the combination with a receptacle adapted to receive snow, of a plurality of outlets feeding water to said receptacle.
3. In a device of the class described, the combination with a receptacle adapted to receive snow and means adapted to feed water thereto, of a plurality of outlets issuing from said receptacle.
4. The combination with snow collecting means, of a plurality of cellular compartments within which the snow may be directed, and means adapted to feed water to each compartment.
5. The combination with snow collecting means, of a plurality of cellular compartments within which the snow may be directed, means adapted to feed water to each compartment, and individual exhaust means for each compartment.
6. The combination with a receptacle adapted to receive snow and means adapted to feed water thereto, of an exhaust conduit, and a plurality of outlets for said receptacle leading to said conduit.
7. In a device of the class described, a scoop having its rear portion subdivided in a plurality of cellular compartments, and means for feeding water to said compartments.
8. In a device of the class described, a scoop having its rear portion subdivided in a plurality of cellular compartments, and means for feeding water individually to each compartment.
9. In a device of the class described, a

- scoop having its rear portion subdivided in a plurality of cellular compartments, exhaust means therefor, and means for feeding water individually to each compartment.
- 5 10. In a device of the class described, a scoop adapted to collect snow, means for feeding water to the rear portion thereof, and means adapted to connect to or disconnect said rear portion from the front portion of said scoop.
11. In a device of the class described, a scoop having its rear portion subdivided in a plurality of cellular compartments, means adapted to connect to or disconnect said rear portion from the front portion thereof, individual water supply means for each compartment, and individual exhaust means for each compartment.
- 15 12. In a device of the class described, a scoop having its rear portion subdivided in a plurality of cellular compartments, an ex-
- haust conduit, means adapted to connect to or disconnect said rear portion from the front portion thereof, individual water supply means for each compartment, and individual exhaust means for each compartment leading to said conduit.
- 20 13. In a device of the class described, a receptacle adapted to receive snow subdivided in a plurality of cellular compartments, means for directing a stream of water within each compartment, means for feeding snow in the path of said streams of water, and exhaust means for each compartment opposite said water supplying means.
- 25 14. The combination of a plurality of snow receiving chambers, a water supplying nozzle within each chamber, means adapted to feed snow to said chambers, and exhaust means for said chambers opposite said nozzles.

MARIO SCHIESARI.
